UNITED STATES PATENT OFFICE.

LAWRENCE F. MUSTEE, OF CLEVELAND, OHIO, ASSIGNOR TO JOSEPH H. MILLER, OF CLEVELAND, OHIO.

FEEDING DEVICE FOR MANGLES.

Application filed September 17, 1921. Serial No. 501,405.

This invention relates to feeding devices for mangles and similar machines, and has for its principal object to provide a device which will feed a row of napkins, towels 5 and the like to a mangle in such a manner that the forward edges thereof will be in alignment.

Another object of the invention is to provide a device of said character which is operated in time from a folding machine so that the aligning forward edges of the napkins, towels and the like will reach a certain position for action thereon by said folding machine.

15 Another object of the invention is to provide a device of said character which is intermittent in operation to enable the loading thereon of the napkins, towels and the like.

20 A further object of the invention is to provide a device of said character which is of simple construction and positive in action.

With the above and other objects in view as will be readily understood, the invention will be hereinafter fully described as illustrated in the accompanying drawings and the novel features thereof will be distinctly pointed out in the appended claims.

25 In the drawings similar characters of reference are used to designate corresponding parts.

Figure 1 is a rear elevation of a feeding device for mangles constructed in accordance with my invention,

Fig. 2 is a side elevation of the same connected in operative relation with a folding machine,

Fig. 3 illustrates a holder of the feeding device in normal position loaded with a napkin,

Fig. 4 is a similar view illustrating the holder in its up position and the napkin after falling therefrom,

Fig. 5 is a plan view to illustrate the forward aligning edges of the napkins after falling from the holders, and

Fig. 6 is a fragmental view of a shelf of a holder with cloth covering the flange thereof.

When napkins, towels and the like are fed into mangles and similar machines by several operators, the forward edges of the same are out of alignment due to the operators being unable to work in unison. The forward edges of the napkins being out of alignment at the beginning, continue thru

the mangle as started, and when thru the mangle, said forward edges of the napkins are still out of alignment. In using a folding machine of the character disclosed in my application No. 346,742, filed December 22, 1919, it is essential that the forward edges of the napkins be in alignment in order that the napkins may be folded evenly. This is the purpose of designing the feeding device of the present invention.

Referring to the drawings, 1 represents the frame of a mangle which supports the usual rollers as 2 over the steam sections 3, and a roller 4 carrying endless belts 5 around a rod or bar 6 serving as a conveyor for feeding napkins, towels and the like to the rollers 2. When napkins are laid upon the belts 5 by several operators standing in front of the roller 4 as is the usual practice, the forward edges of the napkins are not in transverse alignment due to each operator not being able to apply the napkins upon the belts at the same instant and at a uniform distance from the roller 4. As a result of the forward edges of the napkins not being in transverse alignment when entering the mangle, they continue thru and leave the mangle with their forward edges out of transverse alignment. In using a folding machine in connection with the mangle, it is important that the forward edges of the napkins when they leave the mangle should be in transverse alignment, and the present invention was designed to feed the napkins into the mangle with their forward edges in transverse alignment, so that upon leaving the mangle, their forward edges would be in transverse alignment.

Extending from the sides of the frame 1 are up-rights 7 and 8, in which is rotatably mounted a rocking shaft 9 supporting a plurality of dependent holders as 10 having shelves 11 with upturned edges 12 for receiving napkins 13. The upturned edges 12 are preferably covered with cloth 14 or other suitable material for preventing slipping of the napkins. The shaft 9 extends transversely in the same direction as the roller 4, and the shelves 11 of the holders 10 extend rearwardly beyond said roller and at right angles thereto, and are formed on the arc of a circle. The holders 10 are rotatably and slidably adjustable on the shaft 9, to which they are securely fixed by means of set

screws at 15 in any suitable position. For rocking the shaft 9 intermittently crank arms 16 and 17 are fixed to the ends thereof, and to these and to the upper free ends of lever arms 18 and 19, which are fixed to the ends of a shaft 20 rotatably mounted in the frame 1 as at 21, are pivoted links 22 and 23 respectively. An arm 24 is fixed to the shaft 20, and to this is pivoted a rod 25, which is pivotally connected to the upper end of a lever bar 26 pivotally supported by a short shaft 27 carried by brackets 28 and 29. To the lower end of the lever bar 26 is pivoted a rod 30, the other end of which is fixed to a bifurcated head 31 for straddling a shaft 32 of a folding machine indicated by 33. Fixed to the shaft 32 is a suitable cam 34 in the form of a disc for engaging a lug 35 extending from the side of the head 31, and having a recess 36 for receiving said lug. Weighted arms as 37 formed integrally with and extending forwardly from the lever arms 18 and 19 tend to cause the lug 35 of the head 31 to engage the cam 34 and retain the holders 10 in their normal positions for being loaded with napkins. The weights 38 and 39 may be adjusted to any suitable position upon their arms by means of set screws or any other suitable means. Each time the cam 34 advances to the proper position for allowing the lug 35 of the head 31 to enter the recess 36 thereof, the weights 38 and 39 cause the holders 10 to move forwardly, and then they are moved rearwardly to normal position by the action of said cam. This produces a quick forward swing of the holders 10, a slow return, and a rest at their normal positions to give time for the loading thereof with napkins.

In practice, and when the holders 10 and all parts of the machine are in their normal positions as best shown in Fig. 2; the operators, standing before the roller 4, hang damp napkins 13 over the edges 12 and upon the shelves 11 of the holders 10 with their forward edges 40 against the backs of the holders as shown in Fig. 3. As the shaft 32 of the folder 33 revolves, it rotates the cam 34, and the instant the recess 36 thereof is opposite the lug 35 of the head 31, said lug moves therein due to the weights 38 and 39; which action causes the holders 10 to swing forwardly to the position shown in Fig. 4, and the napkins 13 fall therefrom upon the belts 5 with their forward edges 40 in alignment as shown in Fig. 5. As the cam 34 continues to rotate, it forces the lug 35 out of the recess thereof, and thereby returns the holders 10 to their original or normal positions, and retains them at rest to be loaded by the operators. Each set of loaded napkins fall upon the belts 5 at regular intervals with their forward edges in alignment, and as they enter the mangle with their forward edges in alignment, they leave in the same

relative positions, and as the movement of the holders is timed with the action of the folding machine, each set of napkins reach the folding machine at the proper time with their forward edges in alignment. 70

It is to be understood that slight changes in the details of construction may be made for carrying out the purpose of this invention within the scope of the claims.

Having fully described my invention, 75 what I claim is:

1. In a feeding device for mangles, the combination of a plurality of holders, each holder having a shelf for supporting a piece of flexible material, each shelf 80 having a turned up edge for retaining the piece of flexible material upon the shelf, the turned up edge being covered with means for preventing slipping of the pieces of flexible material, and means for actuating the 85 holders for allowing the pieces of flexible material to fall therefrom, substantially as described.

2. In a feeding device for mangles, the combination of a plurality of holders for 90 supporting pieces of flexible material, a rotatable shaft, the holders being adjustably fixed to the shaft for adjustment longitudinally and rotatably thereon, means tending to actuate the shaft in one direction for allowing the pieces of flexible material to fall from the holders, and means for actuating the holders to their original positions, 95 substantially as described.

3. In a feeding device for mangles, the 100 combination of a plurality of holders for supporting pieces of flexible material, a rotatable shaft, the holders being fixed to the shaft, means including a weight tending to actuate the shaft in one direction, and means 105 including a cam for actuating said shaft in the other direction, substantially as described.

4. In a feeding device for mangles, the combination of a plurality of holders for 110 supporting pieces of flexible material, a rotatable shaft, the holders being fixed to the shaft, cranks fixed to the shaft, lever arms, links connecting the lever arms to the cranks, weighted arms extending from the lever 115 arms tending to actuate said holders in one direction for allowing the pieces of flexible material to fall therefrom, and means for actuating the lever arms to return the holders to their original positions, substantially as described. 120

5. In a feeding device for mangles, the combination of a plurality of holders for 125 supporting pieces of flexible material, a rotatable shaft, the holders being fixed to the shaft, cranks fixed to the shaft, lever arms, links connecting the lever arms to the cranks, weighted arms extending from the lever arms tending to actuate said holders in one direction for allowing 130

- the pieces of flexible material to fall therefrom, a bifurcated head, means connecting said lever arms to the head, the head having a lug, a cam, the cam being adapted to engage said lug and having a recess for receiving the same to retain the holders in normal position and to allow said weighted arms to actuate the holders, substantially as described.
- 10 6. In a feeding device for mangles, the combination of a rotatable shaft, holders fixed to the shaft, shelves forming a part of the holders and extending rearwardly therefrom, the shelves being adapted to support pieces of flexible material, and means for actuating the shaft for causing the holders to move forwardly for carrying said mate-
- 5

rial and for allowing said material to fall therefrom, substantially as described.

7. In a feeding device for mangles, the combination of a rotatable shaft, holders fixed to and depending from the shaft, shelves forming a part of the holders and extending rearwardly therefrom, the shelves being adapted to support pieces of flexible material, means for actuating the shaft for causing the holders to move forwardly on the arc of a circle for carrying said material forward and allowing it to fall therefrom, and means for returning the holders to their original positions, substantially as described.

In testimony whereof I affix my signature.
LAWRENCE F. MUSTEE.
